UNITED STATES PATENT OFFICE

FRANK R. CHESTER, OF NEW YORK, N. Y., ASSIGNOR, BY MESNE ASSIGNMENTS, TO CHESTERFIELD CONTROL COMPANY, OF DOVER, DELAWARE, A CORPORATION OF DELAWARE

GAME

Application filed July 2, 1927. Serial No. 203,056.

This invention relates to a game of improved construction, and aims specifically to provide a game of the golf type.

It is an object of the invention to construct a device of this character in which the results accomplished are not achieved by the element of luck, but, rather, are dependent upon the skill with which the operator actuates the game mechanism.

10 A further object of the invention is that of providing a game of this type in which a number of different golf shots may be played, and in which, preferably, these shots will be executed in proper sequence.

15 Another object is that of furnishing a game which will embody a minimum of mechanical parts, each individually rugged and readily assembled, to provide a game apparatus the mechanism of which may be operated over long periods of time with freedom from mechanical difficulty.

20 A still further object is that of providing a game of this type the operation of which will preferably be coin-controlled by means of mechanism consistent with the achievement of the results outlined in the preceding paragraph, and in which, upon certain shots being accomplished, the playing of the game may not be continued until a second token or coin has been deposited within the control mechanism.

25 Other objects of the invention will in part be obvious and will in part appear herein-after.

30 The invention accordingly comprises the features of construction, combination of elements and arrangement of parts which will be exemplified in the construction hereinafter set forth, and the scope of the application of which will be indicated in the claims.

35 For a fuller understanding of the nature and objects of the invention reference should be had to the following detailed description taken in connection with the accompanying drawings, in which:

40 Figure 1 is a sectional plan view of a game embodying one form of the present invention;

45 Fig. 2 is an end view thereof;

Fig. 3 is a transverse sectional view;

Fig. 4 is a longitudinal sectional view, certain of the parts being broken away to disclose the underlying construction; and

Fig. 5 is a sectional view showing the manner in which the club is mounted.

55 In these views a cabinet is shown for enclosing the game and operating mechanism therefor, this cabinet preferably embracing a base 10, from which walls 11 extend upwardly; the forward end wall preferably having a cut-out portion within which a glass 12 is positioned, and these walls supporting a glass cover 13 through which the interior of the cabinet may be viewed.

60 Positioned above the base 10 is a deck 14, in the present instance inclined to a common low point 15, and the upper surface of which preferably is painted or otherwise decorated to simulate in appearance a fairway. Arranged in advance of the rear wall of the cabinet is what might be termed a target member including a plate 16 formed with an opening 17. The field 14 is also formed with an opening 18 in advance of the opening 17 and preferably in line therewith, this opening being normally closed against the entrance of a missile by means of a plug 19.

70 Positioned upon the deck 14 is a figure simulating in appearance a golfer, this figure including nether and body portions 20 and 21 respectively, the former of which is fixed upon the deck, and the latter being axially movable with respect to the former. Se- 75

80 cured to the hands of the figure is a minute golf club 22, preferably of the mashie type, the shaft of which extends through the portion 21 as in Fig. 5. In the normal position of the figure the head of this club lies, as shown in Fig. 1, adjacent to the rear of the 85 most depressed portion of the field. Thus it will be obvious that if a missile 23 lies at this point on the field and the body of the figure is swung, the club head will contact with the missile, and, according to the violence of such contact, the latter will be impelled across the deck and toward the opening 18 thereof, or will be pitched toward the target and the opening 17 of the latter.

90 95 100 With a view to operating the figure in this

manner, a shaft 24 extends transversely of the deck and below the same and mounts at one of its ends a bevel gear 25 meshing with a similar gear 26 secured to the shaft 27, the latter extending through the entire nether portion of the figure and being fixedly attached to the body portion thereof; it being here noted that the ratio between the gears 25 and 26 is preferably 2 to 1. At its opposite end 10 the shaft 24 mounts a crank 28, to which one end of a pitman 29 is attached, the opposite end of the latter being secured to a bell-crank lever 30 pivotally mounted as at 31 and having its outer arm extending beyond 15 the cabinet end; this arm preferably terminating in a finger contact portion 32 which may be movable within the confines of a guard 33 extending from the cabinet wall. Furthermore, with a view to properly limiting 20 the movements of the bell-crank lever 30, adjustable stops 34 may be provided within the body of the cabinet and arranged one above and the other below the edges of the outer arm of the bell-crank. Thus, as the 25 latter is rocked it will be obvious that the shaft 24 will be given a partial rotation in order to pivot the body portion 21 of the figure and to swing the head of the club carried thereby; it being here noted that a spring 30 35 is preferably provided with a view to maintaining the parts in the position shown.

To the rear of the target 16 a plate 36 is 35 swingingly mounted by another bell-crank lever 37, the upper arm of which terminates in a downwardly-extended rounded catch-portion 38. Cooperating with this portion is a rounded shouldered portion 39 formed at the upper end of a still further bell-crank lever 40, which is mounted by a shaft 41 and 40 has its lowermost arm extending below the upper end of the deck and carrying the plug 19, which normally closes the opening 18. A spring 42 may be employed to normally tend to swing the plug 19 downwardly within the 45 slotted guide-member 43, this spring thus transmitting to the upper arm of the bell-crank 40 a tendency to move inwardly, which is normally prevented by virtue of the cooperation between the rounded catch-portion 38 and the rounded shouldered portions 39. To 50 the rear of the plate 16 and below the opening 17 a trough 44 may be positioned, this trough as shown in the present exemplification extending downwardly and communicating at 55 its lower end with an opening 45 formed in the side wall portion of the plate 16. Thus, with the missile 23 positioned upon the field and the parts disposed as shown, if the shaft 24 is rotated, only a "pitch" shot can properly 60 be made, for the reason that the plug 19 is under those conditions closing the opening 18, while the opening 17 is unobstructed. After each failure of the missile to enter the opening 17, due to an over- or under-playing of 65 the shot, the missile will rebound and roll

over the deck 14 until it again lies at the lowermost portion thereof and in advance of the club head, which in the interim has returned to its normal position. However, upon the missile passing through the opening 17, it 70 will obviously strike against the plate 36 and be deflected thereby into the trough 44, from which it will return automatically to the upper surface of the deck and resume its normal position by passing through the opening 45. 75 Incident to the contact of the missile with the plate 36 as it passes through the opening 17 and the necessary force exerted by such contact, the bell-crank lever 37 will be swung rearwardly and, as a consequence, the catch-portion 38 will clear the shouldered portion 39, thus permitting the bell-crank lever 40 to swing forwardly and downwardly under the influence of the spring 42 to clear the opening 18. Incident to such swinging, the upper arm 80 of the bell-crank lever will also engage the rear edge of the downwardly-extending arm of the bell-crank lever 37 to thus force the plate 36 to a position at which it lies immediately to the rear of the opening 17 so as to 85 prevent the re-entrance of the missile through this opening. By actuation of the bell-crank lever 30 the figure may now be caused to execute putting shots until the missile passes through the opening 18 into the guide 43 and 90 rests against the upper surface of the lowered plug 19. In such position it is obvious that this missile will not return to the deck, and, as a consequence, the playing of the game must 95 be discontinued after the achievement of the two desired shots.

It is preferred that a game of this type be coin-controlled, i. e., that the return of the missile to the deck be effected by means of token-controlled mechanism. With a view 100 to providing a desirable mechanism of this character, the present invention also embraces a structure, such as the following: A plate 46 is secured to the upper edge of one of the cabinet side walls and extends over the 105 upper face of the cover thereof, this plate being formed with a token or coin slot 47 from which a coin chute 48 extends downwardly. A guide 49 within which a block 50 is movable, is interrupted in line with the chute 48 to provide a passage of a size adequate for the 110 free passage therethrough of a coin or token 51. A pusher-foot 52 is also movable within the guide-member 49 and is secured to the pitman 29 to move with the latter; the normal 115 position of these parts being shown in Fig. 4. Thus, if a coin is dropped through the chute 48 it will come to rest in the position shown in this figure, and upon the finger portion 32 of the bell-crank lever 30 being depressed the 120 pusher-foot 52 will press against the token or coin 51 to project the block 50 until such time as the coin or token 51 moves to a position 125 in line with a chute 53 extending from an opening in the lower edge of the guide- 130

member 49. Upon this element aligning with such latter chute, it will pass downwardly through the same into a coin box (not shown). Secured to the block 50 is a rod 54, the rear end of which is connected to the upper end of an arm 41' secured to the shaft 41. Consequently, as the block 50 is moved under the influence of the pusher-foot 52, and by virtue of the connection provided by the token or coin the upper arm of the bell-crank lever will be swung rearwardly and its lower arm will be swung upwardly. This will result first in the plate 36 moving rearwardly to the position shown in the figure under consideration, and, secondly, in an interengaging of the catch-portion 38 with the shouldered portion 39 and a plugging of the opening 18. Upon this position of the parts being established, and upon the catch 32 being released the token or coin will move downwardly through the chute 53, and these parts will maintain their position. The game now may be played in the manner above described to effect (a) a pitch or approach shot, resulting in the missile passing through the opening 17; and (b) a putt, resulting in the missile passing through the opening 18. Upon the completion of the former shot it will be apparent that as the bell-crank lever 40 returns to what might be termed its non-set position, the rod 54 and plug 50 are free to return to their initial position and from which position they will be moved only by the depositing of a token or coin within the chute 48 and a subsequent actuation of the finger-portion 32 of the bell-crank lever 30.

Finally, it will be observed that if a game such as has been illustrated is constructed within the teachings of the present invention, a single lever will serve to effect both the operation of the coin control and the mechanisms of the game, thus reducing to a minimum all mechanical difficulties.

Thus, among others, the objects of this invention have been accomplished, and since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having described my invention, what I claim as new and desire to secure by Letters Patent is:

1. A golf game, including a deck and a back-stop, each formed with an opening, a missile-impelling member mounted upon said

deck, means for actuating said member to toss a missile supported upon the deck surface toward the opening in the back-stop or move said missile over said deck toward the opening in the latter, and means associated with each of said openings and connected to alternately obstruct one of the same. 70

2. A golf game, including a deck and a back-stop, each formed with an opening, a missile-impelling member mounted upon said deck, means for actuating said member to alternately toss a missile toward the opening in the back-stop or move said missile over said deck toward the opening in the latter, means for closing both of said openings to the passage of the missile, and means connecting said last-named means to alternately have one of said openings closed while the other affords free passage to a missile. 75

3. A golf game, including a deck and a back-stop, each formed with an opening, a missile-impelling member mounted upon said deck, means for actuating said member to alternately toss a missile toward the opening in the back-stop or move said missile over said deck toward the opening in the latter, a plate to the rear of said back-stop opening, means for closing said field opening, and trigger mechanism connecting said plate and to be actuated by the impact of a missile 80 against the former to release the latter. 85

4. A golf game, including a deck formed with an opening, a plug for normally closing said opening, means for retracting said plug to permit the passage of a missile through said opening, and controlling means for moving said plug to its initial position. 100

5. A golf game, including a deck formed with an opening, a plug for normally closing said opening, means for retracting said plug to permit the passage of a missile through said opening, a missile-impelling member mounted upon said field, a controlling mechanism connected with said plug for moving the same, and means for actuating both said mechanism and said impelling member. 105

6. A golf game, including a deck and a back-stop, each formed with an opening, a missile-impelling member mounted upon said field, a plate to the rear of the back-stop opening, a plug adjacent the field opening, means connecting said plate and plug to prevent the passage of a missile through one opening simultaneously with permitting such passage through the second opening, actuating means connected with said impelling member, and a controlling mechanism connected with said plate and plug to establish the initial positions thereof, said actuating means being also connected with said controlling mechanism 115 to operate the same. 120

7. A game including a deck formed with a target opening, a back-stop also formed with a target opening, a missile-impelling member mounted upon said deck to pitch a mis- 125 130

sile towards said back-stop opening and to roll the same to said deck opening, means for alternately closing each of said openings and means associated with one of said openings for retaining a missile impelled to the same.

5 8. A game including a deck, a back-stop, said deck and back-stop being each formed with an opening, a missile-impelling member to pitch a ball towards said back-stop opening, means for closing said opening after a missile has been successfully impelled towards the same, said deck opening providing a missile retaining element, means associated with said latter opening for delivering a retained missile on to the deck, and means for connecting said last named means to the closing means for said back-stop opening to close said deck opening upon said back-stop opening being accessible to a missile.

10 9. A game including a deck, a back-stop, said deck and back-stop being each formed with an opening, a missile-impelling member to pitch a ball towards said back-stop opening, means for closing said opening after a missile has been successfully impelled towards the same, means for delivering such missile back to the deck and adjacent the impelling member, said deck opening providing a missile retaining element, means associated with said latter opening for delivering a retained missile on to the deck and means for connecting said last named means to the closing means for said back-stop opening to close said deck opening upon said back-stop opening being accessible to a missile.

15 10. A game including a deck providing a green, a ball impelling member mounted upon said deck, a back-stop extending from said deck and being formed with a driving opening, said deck being formed with a putting opening and means associated with each of said openings for closing one of the same when the other is accessible to a ball resting upon said deck.

20 11. A game including, in combination, a deck, a missile impelling member disposed upon said deck, mechanism for actuating said member, target portions, mechanism for "setting" said target portions, said mechanisms being adapted to receive a token to operatively couple the same whereby an initial operation of said actuating mechanism results in a "setting" of the target portion.

25 55. In testimony whereof I affix my signature.
FRANK R. CHESTER.
